UNITED STATES PATENT OFFICE.

FRANKLIN P. NALE AND EPHRAIM J. HUDDNALL, OF BIRMINGHAM, ALABAMA.

BACK FOR FIREPLACES.

1,154,045.

Specification of Letters Patent. Patented Sept. 21, 1915.

Application filed March 23, 1914. Serial No. 826,663.

To all whom it may concern:

Be it known that we, FRANKLIN P. NALE and EPHRAIM J. HUDDNALL, citizens of the United States of America, residing at Birmingham, in the county of Jefferson and State of Alabama, have invented certain new and useful Improvements in Backs for Fireplaces, of which the following is a specification.

10 Our invention relates to improvements in fire backs and has for its object to provide a novel arrangement of dust flues disposed so as to catch and carry off the dust that is swept into the fireplace and prevent its escape into the room.

15 A further object of our invention is to so arrange the dust flues that they may serve to prevent the back becoming sufficiently heated to be injured while at the same time they do not interfere with the normal draft to the fire nor do they chill the back sufficiently to substantially affect its heat radiating capacity.

20 Our invention further comprises the details of construction and arrangements of parts which are hereinafter more particularly described and claimed, reference being had to the accompanying drawings which form a part of this specification, and in which:—

25 Figure 1 is a front elevation of a fireplace having our improved fire back. Fig. 2 is a vertical sectional elevation taken on the line $x-x$ of Fig. 1. Fig. 3 is a horizontal section taken on the line $y-y$ of Fig. 2. Fig. 4 is a detail view of the fire back cast as an integral body.

30 Similar reference numerals refer to similar parts throughout the drawings.

35 According to the drawings, the chimney 1 is of customary construction and the fireplace therein is formed with side walls 2 and a back 3, which back may be made of brick or built up as a part of the chimney, or may be formed as an integral molded article of fire clay, as illustrated in Fig. 4. This fire back is provided with a front wall which curves toward the front of the grate at its upper end 4 and is provided with vertical side grooves 5 which extend lengthwise down its sides and into which the side walls 2 of the fireplace interfit, as shown in Fig. 8, to prevent the back falling out. The fireplace is

provided with a grate 6 of any suitable design. Below this grate and on the level of the hearth 55 7 of the fireplace we provide a pair of horizontal flues 8 in the bottom of the back 3. These flues have their side walls slightly tapered upwardly and are spaced well apart so as to bring them near each side of the fireplace. 60 These horizontal flues 8 merge into vertical flues 9 which have their outer side walls tapered and which are preferably larger in cross-sectional area than are the flues 8. Preferably these flues 9 are disposed in line 65 with the flues 8 and are of substantially the same size throughout. They are arranged adjacent to the sides of the back 3 so as to leave the middle portion of the back of normal thickness and free of flues. At their upper ends these vertical flues open into the chimney flue 10 so that a continuous draft is maintained through the flues 8 and 9 by the normal chimney draft. We arrange the flues 70 8 at the sides of the fireplace to avoid interference with or diversion of the draft for the fire in the grate for the chimney naturally draws the incoming air toward the center of the fireplace and air therefore drawn toward the sides at the bottom of the fireplace 75 will have practically no effect on the main draft and yet will carry off the ashes and dust swept into the fireplace. By arranging our flues 8 and 9 adjacent to the sides of the fireplace we not only do not rob the fire of 80 any substantial part of its draft but we avoid chilling the center or highly heated part of the back enough to affect its efficiency in radiating heat into the room. The draft of air through the flues 9 will be sufficient, 85 however, to prevent the back becoming so overheated as to be injured thereby. 90

95 We prefer to make the whole back as an integral molded article of fire clay for which reason the flues 8 and 9 are tapered to permit the free withdrawal of the patterns therefrom. However the back can be formed in one or more parts or made of brick as may be desired without departing from our invention.

100 Having thus described our invention, what we claim as new and desire to secure by Letters Patent, is:—

105 A fireback for fireplaces formed along its bottom with horizontal grooves and at its back with vertical grooves communicating

with the horizontal grooves, whereby when the fireback is in its operative position, flues will be formed leading from the hearth beneath the grate and upward between the fireback and the rear wall of the chimney flue, and opening into the chimney flue at a point opposite the direct outlet of the fireplace for the products of combustion.

Copies of this patent may be obtained for five cents each, by addressing the "Commissioner of Patents, Washington, D. C."

In testimony whereof we affix our signatures in presence of two witnesses.

FRANKLIN P. NALE.
EPHRAIM J. HUDDNALL.
